UNITED STATES PATENT OFFICE.

ROBERT S. JOHNSON, OF GRAND RAPIDS, MICHIGAN.

METALLIC CRATE.

SPECIFICATION forming part of Letters Patent No. 739,006, dated September 15, 1903.

Application filed February 3, 1903. Serial No. 141,640. (No model.)

To all whom it may concern:

Be it known that I, ROBERT S. JOHNSON, a citizen of the United States, residing at Grand Rapids, in the county of Kent and State of Michigan, have invented certain new and useful Improvements in Metallic Crates; and I do hereby declare the following to be a full, clear, and exact description of the invention, such as will enable others skilled in the art to which it appertains to make and use the same, reference being had to the accompanying drawings, and to the figures of reference marked thereon, which form a part of this specification.

This invention relates particularly to portable and knockdown crates for shipping poultry, vegetables, fruit, and the like and to shipping-crates in general.

The object of the invention is to produce a crate which will fold into a small space when not in use. A further object is to form such a crate of wire or metal, giving greater strength and cleanliness than would otherwise be the case.

With this and other objects in view an embodiment of the invention is herein described in which the sides and ends of the crate comprise standards formed of twisted wire connected by wire rods. The folding effect is permitted by looping the ends of the wires into the corner-standards, forming hinge connections whereby the sides and ends may be collapsed and folded together against each other.

Instead of the twisted wire herein described the standards may be formed of pressed steel, with holes for the loops of the wires, or of wire rods wound and looped to engage the loops of the side wires.

In the accompanying drawings, Figure 1 is a perspective view of the crate set up, and Fig. 2 is a perspective view of the crate folded.

Referring specifically to the drawings, 6 indicates the standards, which are therein shown as formed of twisted wire. The twists of the corner-standards are open at intervals, forming spaces to receive the loops 7^a of the horizontal wires 7, forming the sides and ends of the crate. The wires are stayed at the middle by passing through open twists in the middle standards, as at 6^a. The loop con-

nection to the corner-standards forms hinges which permit the sides and ends to be collapsed, when the bottom of the crate is removed, into substantial parallelism, as shown 55 in Fig. 2. The number and distance apart of the wires forming the sides and ends of the crate are suitable and according to the use to which the crate is to be put.

The bottom of the crate is indicated at 8 and rests at its ends upon the lower wires of the ends of the crate. The bottom is somewhat longer than the inside measurement of the crate, and it is inserted through the top and sprung into place by slightly forcing out 65 the ends of the crate, which action is permitted by the elasticity of the metal. The bottom is notched at each end, as at 8^a, to receive the middle end standards, whereby it is held in place.

Instead of the wooden bottom a wire bottom may be substituted formed of a wire construction of similar shape inserted and retained by the same means as shown in connection with the wooden bottom. It will be 75 seen that the bottom may be removed by springing the ends outwardly, and when so removed the ends and sides can be folded, as above described, and they cannot be folded unless the bottom is removed.

The cover of the crate is preferably formed of wire in two parts, (indicated at 9,) each of which is hinged by wire loops 10 to the top wires of the sides of the crate. This permits the parts of the cover to be lifted up and folded out 85 and down against the outside of the sides of the crate, in which position they do not interfere with the folding operation, but lie close against the sides and occupy very little space. One of the parts of the cover may 90 have a hand-door 11 for use with poultry.

The crate formed as above specified will be comparatively cheap and of very little weight and when empty may be collapsed to occupy very little space and make a compact 95 package for shipping.

What I claim as new, and desire to secure by Letters Patent, is—

1. In a crate, the combination with elastic walls formed of spaced wires joined at the 100 corners, of a removable rigid bottom longer than the inside of the crate, the ends of the

bottom being sprung within the openings between the wires forming the walls and supported on the lower wires thereof.

2. In a folding crate, the combination with 5 elastic walls formed of horizontal spaced wires flexibly joined at the corners and having vertical standards connecting the wires, of a removable rigid bottom longer than the inside of the crate, sprung within and supported by

the walls and having notches receiving the 10 standards.

In testimony whereof I affix my signature in presence of two witnesses.

ROBERT S. JOHNSON.
